INCINERATOR WITH DAMPER CONTROLLED INTERNAL FLUE

Virgil B. Remore, Cummings, Calif.

Application October 14, 1949, Serial No. 121,348

2 Claims. (Cl. 110—18)

1

This invention relates to an incinerator and more particularly to an incinerator adapted for installation in parks, resorts and picnic grounds or the like for the disposal of garbage and trash.

The primary object of this invention is to dispose of trash and garbage without perceptible smoke or odor, with a minimum consumption of fuel, and within a minimum of time.

Another important object of this invention is to provide a compact oil burning gravity fed incinerator that will inexpensively burn to a minute ash any type of garbage and trash by consuming the garbage or trash at a high rate of disintegration.

Another object of this invention is to provide an incinerator from which the ashes may be easily removed, which may be easily cleaned, and which may be easily erected and dismantled.

These and ancillary objects and other structural features of merit are attained by this invention, a preferred embodiment of which is set forth in the following description and illustrated in the accompanying drawings, wherein:

Figure 1 is a front elevational view of an incinerator, constructed in accordance with the principles of this invention, and showing the hood in its normal position seated on the top of the body and in an open dotted position;

Figure 2 is a top plan view;

Figure 3 is a vertical sectional view taken substantially on the plane of line 3—3 of Figure 4, looking in the direction of the arrows;

Figure 4 is a transverse sectional view, taken substantially on line 4—4 of Figure 3, looking in the direction of the arrows and illustrating the grate construction;

Figure 5 is a transverse sectional view taken on line 5—5 of Figure 3, and looking in the direction of the arrows, and,

Figure 6 is an enlarged vertical sectional view taken substantially on line 6—6 of Figure 1, and looking in the direction of the arrows, to illustrate the grate structure.

Referring now more particularly to the drawings, this invention generally designated by the character reference 10 comprises a vertically disposed cylindrical metal body 12, which is provided with horizontally disposed alternating ribs 14 and grooves 16.

A conical shaped hood 18 is hingedly secured as at 20 to the upper edge of the body and is formed at its lower end with an annular flange 22, adapted to engage the outer surface of the upper edge of the body and retain the hood thereon.

The hood terminates at its minor end or upper end in an upwardly extending cylindrical outer

2

flue 24 from the upper end of which extends in a transverse plane a stack cap 26. The cap 26 is formed integrally with the stack or outer flue 24 and the opposing ends 28 and 30 thereof extend beyond the sides of the stack. The openings formed thereby are covered with a fine mesh screen 32, so that screen outlets are provided for the products of combustion but burning pieces of garbage or trash are captivated within the incinerator.

Means is provided for swinging the hood from its seated position outwardly from the body and for retaining the same in a horizontal detached position, as illustrated in Figure 1. The means includes an angular handle 34 which is pivotally secured at 36 to a laterally extending perforated ear 38 formed integrally on the outer surface of the side wall of the hood. The hood can be held in the desired open position by placing the lower unattached end 40 of the handle in the selected groove 46 of the body, whereby garbage or trash may be inserted through the open top of the body, without the necessity of holding the hood in an open position.

The lower portion of the body forms a firebox 42, a portion of the lower wall of the body being formed with an air inlet opening 44 and the adjacent portion of the body being bent outwardly to form parallel wings 46 and 48. The wings are connected at their outer lower edges by an angle iron 50.

A cylindrical housing 52 is vertically disposed centrally within the firebox and constitutes a burner, which includes a helical column 54 disposed within the housing and terminating at the upper end thereof in a four-way jet 56. A tube 58 is formed integrally with the lower end of the burner coil and is adapted for association with a fuel connection in a conventional manner.

40 A sliding or vibrating grate 60 is horizontally disposed above the upper end of the housing and is vertically spaced therefrom, the grate being mounted on a pair of parallel rails 62 and 64. An inverted conical shaped basket-type oscillating grate 66 is disposed above the sliding grate and the major or upper end 68 thereof is provided with laterally extending circumferentially spaced trunnions or hangers 70 which are adapted to rest slidably on angle members or brackets 72 fastened as at 74 to the side walls of the body. Thus, the basket grate is suspended in an inverted position for limited oscillation above the sliding grate 60 by means of the complementary trunnions and flanges or angle members carried by the side walls of the body.

An actuating rod 76 is secured to the sliding

grate and terminates in a laterally extending depending end 78 which is received within a lug 80 formed laterally on a vertically disposed lever or handle 82. The handle 82 is pivoted as at 84 to the vertical portion of the angle iron 50. The lever or handle is received within the bifurcated end 86 of a handle extension 88 for a band 90, the latter being secured around the lower minor end of the basket grate.

An elongated tubular inner flue 92 is centrally disposed within the body and has its lower end positioned within the basket grate. The inner flue is horizontally corrugated and formed with a plurality of perforations 95. The flue is supported by a suspension rod 94 which is transversely disposed through the opposing sides of the body. A damper 96 is pivotally secured as at 98 to the upper end of the flue and is adapted to seat on the upper end of the flue and functions as a cap to force the flame outwardly through the perforations 95 of the flue. The damper is controlled by a link rod 100 and a bell crank 102 pivotally secured as at 104 to the link rod and fixed on the suspension bar 94. Thus, rotation of the extending end of the suspension bar rotates the crank and closes the damper in a similar manner, the rotative movement of the crank is translated into an upward sliding movement of the link rod and an outward swinging movement of the damper for moving the same into an extended open position.

In operation, it can be seen that the hood can be swung open by means of the handle and held thereby in an open position, so that garbage and trash can be deposited into the body, the garbage or trash gravitating toward and into the basket grate. As the material moves downwardly, it is dried and burned in its fall by means of flames passing through the perforations in the flue 92. It can be appreciated that with the hood closed, the articles of combustion will be allowed to pass through the screened openings. The corrugations formed in the body and flue will permit the flames from the burner to pass along the corrugations and evenly heat the body and flue, so that the refuse will be dried upon contacting the flue and body. It can be seen that the refuse will be sifted and completely burned by vibrating or reciprocating the sliding grate 60 and oscillating the basket grate 66, so that a minute and fine ash will be deposited in the firebox, from which it can be easily removed through the opening therein. The lever or handle 82 thus constitutes common means for actuating both of the grates. By swinging the handle 82 laterally on its pivotal mounting 84, the upper grate 66 will be oscillated on the brackets 72 through the elements 66, 88, 90, etc. There is enough resiliency and play in the mem-

bers 76, 78, 80, etc., to permit this. Then, by actuating the handle 82 longitudinally in the yoke 86, the lower grate 60 will be vibrated or reciprocated longitudinally on the rails 62 and 64 through the rod 76. There is sufficient looseness or play in the pivotal mounting 84 of the handle 82 to permit such actuation of said handle.

However, while one embodiment of this invention has been shown, it is to be understood that certain other embodiments can be carried out, as coming within the spirit and scope of the appended claims.

Having described the invention, what is claimed as new is:

1. An incinerator comprising a vertical cylindrical casing having an air inlet in its lower portion and an outlet in its upper portion for the products of combustion, a grate in said lower portion of the casing, a horizontal, manually operable shaft journaled diametrically in an upper portion of the casing, a perforated, vertical flue, open at its ends, journaled on said shaft and depending therefrom in the casing in spaced, concentric relation thereto and communicating therewith adjacent the grate and the outlet at its lower and upper ends respectively, a damper hingedly mounted on the flue for closing the upper end thereof, and means operatively connecting the damper to the shaft for actuation thereby.

2. An incinerator comprising a vertical cylindrical casing having an air inlet in its lower portion and an outlet in its upper portion for the products of combustion, a grate in said lower portion of the casing, a horizontal, manually operable shaft journaled diametrically in an upper portion of the casing, a perforated, vertical flue, open at its ends, journaled on said shaft and depending therefrom in the casing in spaced, concentric relation thereto and communicating therewith adjacent the grate and the outlet at its lower and upper ends respectively, a damper hingedly mounted on the flue for closing the upper end thereof, and means operatively connecting the damper to the shaft for actuation thereby, said means comprising an arm fixed on the shaft, and a link pivotally connected to said arm and to the damper.
